CLAIM

The original design for a container with invertible tray and flaps, as shown and described.

DESCRIPTION

FIG. 1 is a perspective view of the container with invertible tray and flaps according to the present design;

FIG. 2 is a top view of the design of FIG. 1;

FIG. 3 is a perspective view of the design of FIG. 1 with open lid; and,

FIG. 4 is a perspective view of the design of FIG. 1 with the tray inverted.

1 Claim, 4 Drawing Sheets

FIG. 1

FIG. 2

FIG. 3

FIG. 4
